United States Patent

Des. 242,085

Patented Oct. 26, 1976

242,085

RAZOR HANDLE

Martin V. Maloney and David O. Chase, Skaneateles,
N.Y., assignors to Philip Morris Incorporated

Filed May 27, 1975, Ser. No. 580,883

Term of patent 14 years

Int. Cl. D28—03

U.S. Cl. D95—3 A

FIG. 1 is a perspective view of a razor handle showing our new design.

FIG. 2 is a front elevational view thereof, the front and rear sides being identical.

FIG. 3 is an edge elevational view.

FIG. 4 is a top plan view.

FIG. 5 is a bottom plan view.

We claim:

The ornamental design for a razor handle, as shown and described.
